UNITED STATES PATENT OFFICE.

ARTHUR H. BALLARD, OF BOSTON, MASSACHUSETTS, ASSIGNOR TO ARTHUR H. BALLARD, INCORPORATED, OF BOSTON, MASSACHUSETTS, A CORPORATION OF MASSACHUSETTS.

WINDOW.

Application filed February 4, 1926. Serial No. 86,096.

This invention relates to windows and consists in improvements designed to render interiorly accessible the outside of the sash for the purpose of easier cleaning and also to increase the weatherproof qualities of the joints formed by the movable sashes.

The invention will be best understood by reference to the following description when taken in connection with the accompanying illustration of one specific embodiment thereof, while its scope will be more particularly pointed out in the appended claims.

In the drawings,—

Fig. 1 is a front elevation showing the sashes and framing of the window embodying one form of the invention, the lower sash being partly raised;

Fig. 2 is a cross sectional elevation taken through the line 2—2 in Fig. 1, the sashes being clamped in closed position;

Fig. 3 is a side elevation in partial section taken on the line 3—3 in Fig. 1, showing the upper sash swung in and down for the purpose of cleaning;

Fig. 4 is a sectional elevation on the line 4—4 in Fig. 5 taken through the hinged attachment of the lower sash;

Fig. 5 is a cross sectional elevation on the line 5—5 in Fig. 4;

Fig. 6 is a side elevation in partial section showing the lower part of the window seen in Fig. 3 but with the lower sash swung back;

Fig. 7 is a section on an enlarged scale taken through one of the supports for the sash clamping devices;

Fig. 8 is a section in plan taken through the hinged attachment for the sash;

Fig. 9 is a detail in end elevation showing the guide slot for the pivot member for the hinged sash attachment;

Fig. 10 is a sectional side view on the line 10—10 in Fig. 7 showing the slot through which the clamping devices may be withdrawn; and

Fig. 11 is a sectional plan view on the line 11—11 in Fig. 2 showing the clamp engaging devices carried by the upper sash.

Referring to the drawings and to the illustrative embodiment of the invention there shown, I have illustrated one form of the invention embodied in a window having upper and lower sashes, the upper sash being vertically fixed and the lower sash capable of being raised or lowered.

The invention, however, as to many of its features is applicable to other types of windows, including those in which both sashes are vertically movable or both vertically fixed, or in which one sash is utilized, or other combinations and variations from the disclosed arrangement.

Herein each sash is rectangular in shape, the lower sash being composed of the upright sash members 13, the horizontal upper sash member 15 and the horizontal lower sash member 17. The upper sash has the vertical side members 19, the horizontal upper sash member 21 and horizontal lower sash member 23. Either or both the sash members may be equipped with two or more panes of glass, but herein the lower sash member is equipped with a single pane 25 and the upper sash with a single pane 27.

The general arrangement of the window framing will be apparent from the drawings, and, as shown, it provides a rectangular space or compartment within which the sashes are located, the side walls of the compartment being formed by the walls 29, the bottom by the wall 31 and the top by the wall 33. The width of this rectangular framing space is such that the side walls 29 provide guides for the lower sash between which the latter is freely slideable for raising or lowering. As will hereafter appear the framing space is also of suitable width to permit either sash to be swung back out of the framing.

The window aperture is divided into upper and lower parts by the cross rail 35, on which the bottom of the upper sash rests. To provide an efficient weatherproof joint between each sash and the frame adapted to exclude moisture, dust and cold, while leaving the sash capable of the movements about to be described, the frame is provided at the outside with seal-forming parts which extend entirely around the periphery of the lower sash and other seal-forming parts extending entirely around the periphery of the upper sash, both sashes being permitted a substantial lateral movement toward and away from such seal-forming parts. Herein the seal-forming parts for the lower sash are composed of the weather strip member 37 circular in cross section and seated in a grooved channel or holder 39 held fixed in the framing outside of the limits of the aperture formed thereby for the lower sash, and the seal-forming

parts for the upper sash by a second weather strip member 41 similarly arranged with reference to the aperture closed by the upper sash. The weather strip members 37 and 41 5 may be of any suitable material, but herein rubber is utilized, the arrangement being such that there is presented to the opposing surface of the sash members of each sash a continuous seal-forming strip, so that when 10 the sash is pressed outwardly against the same the apertures are effectively sealed at all points.

The framing is so constructed as to permit the sash to have a substantial movement of 15 translation laterally or perpendicularly to the plane of the sash, and means are provided whereby, when the sash registers with the aperture, it may be forced laterally to close the joint at the seal-forming parts. When 20 the lower sash is raised it may be pressed against the resilient material of the seal and there held frictionally clamped in any open position.

Any suitable devices may be utilized for 25 this purpose, but referring to the clamping devices for the lower sash, I have provided at each opposite side of the frame and at the inner side of the sash an extended bearing member 43 in the form of an upright rail or 30 plate. This presents to each opposed face of the upright sash member 13 a flat bearing face, which, by suitable actuating devices, may be forced against the sash or withdrawn therefrom. When drawn back from the sash it pro- 35 vides a measure of guidance therefor as the latter is being raised or lowered, but the plate 43 is preferably so adjustable that when un- clamped it will leave the sash free of contact 40 with the weatherproof strip so that the sash may be freely raised or lowered without friction.

To throw the clamp rails 43 into or out of 45 clamping engagement with the sash, the former are each pivotally connected at each end by studs 45 to links 47 which are mounted to swing in the side walls 29 eccentrically with reference to the studs 45. The upper and lower links 47 are joined by the connecting rod 49 so that the latter may be manually 50 moved up or down, swinging the links about the pivotal connection to the side walls and causing the clamp rail, due to its eccentric mounting, to approach or recede from the side members of the window sash.

When the sash is in its lowered or closed 55 position, as represented in Fig. 2, but with the clamping rail retracted, the sash may be freely raised or lowered without friction. In any position of the sash, the clamping rail 60 may be forced against the sash compressing it against the yieldable sealing strip 37. This produces a tight waterproof sealed joint if the sash be down, or firmly holds the sash clamped in position if it be raised.

65 In the disclosed embodiment of the inven-

tion I have made provision whereby the sash, without interference with its necessary functions may be easily moved to provide access to the outside surface of the pane from the interior of the building or other structure in 70 which the window is used. This makes it practicable to clean the outside as well as the inside of the window pane from within.

This object may be secured in various ways, but in the illustrated embodiment of 75 the invention I have arranged the sash so that it may be fulcrumed upon one of its side members, as, for example, the lower sash member 17, and thereby swung back through the framing into some such position as is 80 represented in Fig. 6.

In the disclosed embodiment of the invention I have also made provision for the easy removal of the window sash where such removal may be desired for any purpose. 85

To permit the described movements of the sash for purposes of cleaning or removal, the rails 43 or other clamping devices are preferably so arranged that, although normally providing inner guidance for the sash 90 as the latter is raised or lowered, they may be readily moved out of the path of the sash leaving the frame space free from any interference with the backward movement of the sash through the framing. 95

For this purpose the links 47 are journaled by the pivot pins 51 (Figs. 7 and 8) in the bearing block 53 carried by the side walls 29, each pivot pin having an enlarged inner head 55 which normally prevents its escape from the bearing block. The opening for the bearing block which receives the pin 41 (see Fig. 10) opens above into an enlargement 57 of greater diameter than the enlarged head 55, so that by merely lifting the clamping members the pivot pins 55 pass up into the enlargement 57 and may be easily removed from the framing by slipping the enlarged head of the pivot pins through the enlarged portions 57 of the openings. Obviously they may be 100 replaced with equal facility. 105

It is desirable that the sash, while arranged to be swung back as described and, if required, to be withdrawn from the framing, should be counterbalanced in some measure 115 so that it may be readily raised and, when released by the clamps for lowering, will not close violently under its own weight, but preferably only when assisted by some downward pressure. For this purpose there is 120 provided a spring-actuated lifting device, preferably guided for vertical movement in the framing, the same having a hinged connection to the bottom of the sash arranged so as to permit the lateral movement of the 125 sash as described.

The arrangement of these parts will be seen more particularly in Figs. 4, 5, 6, 8 and 9. The lower frame member 17 of the sash has on its under side at each opposite end a 130

recess into which there fits a hinge block 59 having the shape indicated in Figs. 4 and 5. The hinge blocks interlock with the sash and partake of the movement thereof, but, 5 when the sash is swung back as represented in Fig. 6, the latter may be readily slipped out of engagement with the two blocks freeing it of any connection with the framing and permitting it to be removed therefrom 10 after the clamps have been withdrawn.

Connected to each hinge block, to turn therewith, is a pivot member 61 (Figs. 4, 5 and 8). This pivot member 61 where it engages the block is square in cross section 15 (Fig. 5), being seated in a rectangular slot 63 in the hinge block so that, while the latter and the pivot member turn together, the block is allowed to move laterally with the sash when the latter is clamped against the 20 seal-forming parts by the clamping devices.

The pivot member 61 passes through a vertical guide slot 65 (Fig. 9) in the side wall 29 of the frame and on the outside thereof has an enlarged diameter 67 which is journaled in the guide block 69, the latter adapted to slide vertically in the upright guides 71. The guides 71 and block 69 are of such proportions that a substantial guidance is afforded the lifting device in partaking of the 25 vertical movements of the sash. At its outer end the pivot member is secured by a clamping nut 73 (Fig. 8) to a clip or upright finger 75, the latter connected to the lower end of a spring 77, the upper end of which is secured 30 to the window framing. The spring clip 75 is preferably non-rotatably secured to the pivot member so that the latter, together with the hinge block and spring finger, is adapted to turn as a unit with relation to the guide block 69. Herein the finger 75 fits over a 35 non-circular portion 79 of the pivot member.

The tension of the spring 77 may be of any desired amount, but preferably is such that, 40 acting through the pivot member 61 and hinge block, it will prevent the open sash from dropping to closed position when relieved by the clamps, so that a careless person cannot be injured by the accidental dropping 45 of the sash. The tension, if desired, may be such as to partly raise the sash automatically 50 as soon as the latter is released by the clamps, or may be such as to raise it to its full open position if desired. When the sash is raised 55 or lowered the tension of the spring 77 holds the hinge block 59 in engagement with the sash, and the hinge block, pivot member and guide block 69 move up and down with the sash, the latter being guided by the guides 60 ways 71 which thereby serve to keep the pivot members and the two hinge blocks in a substantially fixed vertical path.

When the clamp rails are withdrawn from the framing as heretofore described, the sash 65 may be swung back out of the framing about

the pivot member 61 into some such position as represented in Fig. 6. In this movement the hinge block and spring finger 75 swing with the sash with relation to the guide block 69, the spring undergoing a slight elongation 70 which tends to counterbalance the weight of the free end of the sash, and the elongation, if desired, may be sufficient to assist in returning the sash to its upright position when the sash pane has been washed. 75

To prevent the spring from raising the lower end of the sash when swung to this position, provision is made whereby the hinge block is locked and the action of the spring restrained until the window is again swung 80 back to its normal position. For this purpose the pivot member 61, where it passes through the slot 65 in the side wall 29 (Figs. 8 and 9), is provided with a shouldered piece 81, the lateral dimension of which is reduced 85 to fit and slide through the slot 69 when the hinge block is upright. The opposite or vertical dimension, however, is substantially greater so that it will not enter the slot as represented by the dotted lines in Fig. 9, except when the hinge block is upright. When the sash is in its lowered position the shouldered piece occupies a circular enlargement 88 of the slot 65, so that if the window is swung outwardly as represented in Fig. 6 90 95 the shouldered enlargement is adapted to turn within the slot by the swinging movement of the sash. In so turning, however, it is moved to a position where it cannot enter the main portion of the guide slot 65, so that 100 it remains locked therein against any lifting action of the spring until the window is swung back to its upright position, when the shouldered portion again comes into line with the slot and may move up and down 105 therein freely. The lifting device accordingly, while facilitating the raising and lowering of the sash and permitting the lateral clamping movement thereof, allows the latter to be swung inwardly through the framing 110 and to be there held while its lifting effect is temporarily restrained.

The constructional features of the lower sash per se are claimed in my Patent No. 1,614,942, application for which was filed contemporaneously herewith. 115

Referring now to the upper sash, the latter in the described embodiment is vertically fixed, but is capable of a similar movement of translation to force it outwardly against its 120 weatherstrip 41 by means of clamping devices which, except for the features herein-after referred to, resemble the clamping devices of the lower sash already described.

In order that the clamping devices for the 125 upper sash may not interfere with the raising or lowering of the lower sash, each side member 19 of the upper sash (see Figs. 2 and 11) is provided with a pair of clamp engaging fingers 85 which are seated each in a 130

groove 87 formed in the side walls 29, where they extend back out of the path of the lower sash and present to a suitable bearing lug 89 on the clamp rail (Fig. 11) an outwardly turned shouldered bearing end 91. When the clamps are actuated, therefore, instead of engaging directly with the window sash, they engage the sash indirectly through the fingers 85 which slide in the grooves 87 so as to offer no interference to the vertical movements of the lower sash. The clamp rails for the upper clamps are preferably so located that when actuated to close the upper sash they will offer a measure of guidance to the lower sash when the latter is raised.

In the described embodiment of the invention, the upper sash is also arranged so that it may be swung backwardly through the framing, the construction being such that it may be swung inwardly and downwardly to such an angle that in a room of the ordinary height and with windows of the ordinary height the outside of the upper sash may be readily accessible for the purpose of cleansing to a person standing on the floor. For this purpose the sash is connected to a hinged attachment similar to the hinged attachment of the lower sash, except for the features hereinafter referred to.

30 A hinge block and pivot pin similar to the hinge block 59 and pivot pin 61 are employed, there being also utilized a guide block similar to the guide block 69 and a spring connected to the clip 75 and spring 77. 35 The guide block, however, has a limited movement in its guideways, being brought to rest in its upper position (represented in Fig. 3) by a suitable stop. The interlocking feature presented by the slot 65 and pivot pin 81 is omitted, the pivot pin being freely movable in its guide slot in any inclined position of the sash,—that is to say, the spring is free to lift the hinged attachment when the position of the sash permits, whatever be the inclination of the latter.

When it is desired to swing the sash inwardly, the clamps having been first removed, the sash is swung back about the lower sash member 23 as a fulcrum, the slot 87 in which the clamp-engaging fingers 85 slide, and the fingers themselves, being of such a curved shape as to permit this movement of the sash. As soon as the clamp engaging fingers 85 have emerged from the slots 87, further swinging movement takes place about the hinged attachment of the bottom of the sash and the springs being then free to lift the pivot members, the guide blocks pass to the top of the guideways where they are brought to rest by the stop. This results not only in swinging back the top of the sash, but also in lifting the bottom so that the upper sash finally comes to rest against the sash member 15 of the lower sash in some such position as is represented in Fig. 3, where the outside of the

sash pane can be easily washed or cleaned. To prevent the sash dropping out of its hinge block when moved to this position, the latter may be normally held in place by the employment of set screws or any other suitable fasteners. The window having been cleaned, it is only necessary to tip it back into its original position, causing the clamp-engaging fingers 85 to enter the slots 87, after which the clamp devices may be replaced in position and the window clamped tight against its weather strip, as represented in Fig. 2.

It will be seen that in the inward swinging movement of the sash, after the guide block has reached its upper limit, further downward swinging movement of the window increases the tension on the spring so that the latter serves in part to counterbalance the weight of the sash.

While for purposes of illustration I have herein shown and described one specific embodiment of the invention, it is to be understood that extensive deviations may be made from the mechanical details herein shown as well as the form and relative arrangement of parts, and that numerous other applications of the principles of my invention may be made, all without departing from the spirit thereof.

I claim:

1. A window having a framing provided with upper and lower sashes in which the lower sash may be raised or lowered, seal-forming devices presented to both said sashes and extending around the same, and clamping devices to force the sashes against said seal-forming devices to close the joints thereat, the clamping devices for the upper sash being out of the path of the lower sash to permit the latter to be raised or lowered while said devices are still engaged with said upper sash.

2. A window having a framing provided with upper and lower sashes in which the lower sash may be raised or lowered, seal-forming devices presented to both said sashes and extending around the same, and clamping devices to force the sashes against said seal-forming devices to close the joints thereat, the clamping devices for the upper sash being out of the path of the lower sash but adapted to afford guidance thereto when raised.

3. A window having a sash provided with a framing presenting exterior bearing surfaces for the sash, clamping devices to force said sash outwardly, and clamp engaging means carried by the window sash and located in grooves in the framing whereby the framing space is left unobstructed by said clamp engaging devices.

4. A window having a framing and a lower sash adapted to be raised and lowered, said framing being provided with external seal-forming parts and said sash being movable

- laterally to engage therewith, clamping devices to force the sash laterally to engage with said seal-forming parts, an upper sash, the frame thereof being also provided with 5 external seal-forming parts, and clamping devices mounted in said framing outside of the path of the lower sash when raised and adapted to press said upper sash outwardly against its seat.
- 10 5. A window having a framing and a lower sash adapted to be raised and lowered, said framing being provided with external seal-forming parts and said sash being movable laterally to engage therewith, clamping devices 15 to force the sash laterally to engage with said seal-forming parts, an upper sash, the frame thereof being also provided with external seal-forming parts, clamping devices mounted in said framing outside of the path 20 of the lower sash when raised and adapted
- to press said upper sash outwardly against its seat, said clamping devices being removable from the path of the upper sash to permit the latter to be moved back through the framing, and a hinged attachment for the 25 bottom of the upper sash to permit the latter to be swung backwardly and downwardly about said lower sash to provide access thereto.
6. A window having a framing and a lower 30 sash adapted to be raised and lowered, and an upper sash having devices mounted in said framing outside of the path of the lower sash when raised but adapted to provide guidance for said lower sash and adapted to press said 35 upper sash outwardly against its seat.

In testimony whereof, I have signed my name to this specification.

ARTHUR H. BALLARD.
